UNITED STATES PATENT OFFICE.

ARTHUR W. K. DOWNES, OF CHICAGO, ILLINOIS.

HEATING APPARATUS.

1,188,050.

Specification of Letters Patent. Patented June 20, 1916.

Application filed October 14, 1913. Serial No. 795,068.

To all whom it may concern:

Be it known that I, ARTHUR W. K. DOWNES, a citizen of the United States, residing at Chicago, in the county of Cook and State of Illinois, have invented a new and useful Heating Apparatus, of which the following is a specification.

My invention relates particularly to self-contained heating-apparatus adapted for use in situations where it is inconvenient to use a regular hot water or steam heating-plant; and my primary object is to provide heating-apparatus of simple and inexpensive construction adapted for economic operation in situations of the character referred to.

The invention is illustrated in its preferred embodiment in the accompanying drawing, in which—

20 Figure 1 represents a side elevational view of heating-apparatus constructed in accordance with my invention; and Fig. 2, an end elevational view of the same.

In the illustration given, A represents a radiator; B, a stand on which the radiator is supported; and C, a steam or vapor generator disposed below the radiator and connected therewith.

25 The radiator may be of the usual construction, comprising coils or sections 1, which are in communication at their lower ends, as indicated at 2. The end sections of the radiator are equipped with feet 3 which rest in bearings or sockets 4 with which the stand B is equipped. The stand B comprises a rectangular lower frame 5 mounted on casters 6; and standards 7 rising from the corners of the horizontal frame 5. The corner uprights 7 are connected by 30 cross-pieces 8 which may comprise castings fitted on the upper ends of the corner uprights 7. The stand may be composed of tubes rigidly connected by fittings, as shown. The radiator is secured on the 35 stand B by means of loops or straps 9 which pass about the connections 2 between the end coils and adjacent coils and have their extremities secured, as indicated at 10, to the cross-piece 8.

40 The generator C may be of any approved type. As shown, it comprises a closed sheet metal vessel 11 having an up-curved bottom 12. The vessel 11 may be of cylindrical form with a curved dome, and the vertical wall depends somewhat below the bottom 12 to afford a skirt or housing 13 within

which is located a Bunsen burner 14 which receives its fuel-supply through the tube 15. The burner 14 may be of any approved type and may be adapted to burn gas, oil or other fluid fuel. The dome of the vessel 11 has connected therewith a tubular T-fitting 16, which is detachably connected, by means of a union 17, with the lower end of the adjacent section of the radiator. The upper end 60 of the T-fitting is equipped with a plug-valve 18, which may be opened to admit water supplied through a small funnel 19. The vessel 11 is shown equipped with a pressure-gage 20, a safety-valve 21, and a sight 70 water-gage 22.

In use, the apparatus is partially filled with water, say to the level indicated by the line 23, after which the valve 18 is closed. The fire is lighted and the air is allowed to 75 pass from the radiator through a vent 24. The steam generated passes through the union 17 of the radiator, and any condensation occurring in the radiator runs back into the vessel 11. The pressure-gage and 80 safety-valve may be dispensed with, if desired, as the system ordinarily works at very low pressure.

The efficiency of the apparatus is high, 85 all heat generated being used in the room. The heat generated at the burner is quickly absorbed by the water and is given out at the radiator, being equably diffused in the room. Moreover, the device is easily lighted and requires little or no attention in operation. 90 It will be noted that the same water is used over and over again, so that there is no objectionable deposition of sediment on the bottom of the vessel 11. A further advantage incident to this type of heating apparatus is that it renders unnecessary, in 95 many situations, the installation of an expensive heating-plant, involving the use of house-piping. Apparatus of the character described may be usefully employed for 100 heating garages, houses and offices not equipped with more elaborate steam or hot water plants. In mild climates, such apparatus will answer every purpose, and even in very cold climates where fluid fuel can 105 be cheaply obtained, the apparatus is highly economical, as well as cheap of insulation and easy of operation. In some localities it may be desirable to use the improved heating apparatus as an auxiliary to a more elaborate heating-plant, for fall and spring use. 110

The generator C is suspended by the

union 17 and T-connection 16. The parts may be readily disassembled; and for shipping purposes, the generator may be packed within the frame or stand B.

5 The foregoing detailed description is given for clearness of understanding only, and no undue limitation should be understood therefrom.

10 What I regard as new and desire to secure by Letters Patent is—

In a device of the character described, the combination of a radiator comprising a series of coils, an end coil having a single threaded opening near the lower end 15 thereof, a stand supporting said radiator at an elevation from the floor, a vapor generator comprising a cylindrical boiler and a

gas burner carried thereby, a pipe connection extending outwardly from the threaded opening in the said end coil, a T-connection 20 carried by said pipe connection, a connection between the downwardly extending branch of said T connection and the boiler providing both a support for the vapor generator, and means of communication 25 between the boiler and the radiator, and a valved boiler filler pipe projecting upwardly from the other branch of said T connection.

ARTHUR W. K. DOWNES.
